ATTACHMENT FOR SMOKING DEVICES

John G. Tarrant, New York, N. Y.

Application March 27, 1934, Serial No. 717,580

13 Claims. (Cl. 131—12)

This invention relates to improvements in smoking devices, such as pipes and cigar and cigarette holders, and more particularly to means for treating and directing the flow of smoke during its passage from the point of origin to the mouth of the smoker.

It is an object of this invention to cool and clean the smoke by providing a device having a combined cleaning and baffling element, thereby increasing the length of the path of flow of smoke from tobacco to mouth.

Another object is to provide a device of the character described having a combined positioning and closure means to adjust the position of the cleaning and baffling element and to close one end thereof.

Another object is to provide a device of the character described in which the said cleaning and baffling element is readily replaceable.

Other and further objects of this invention will be apparent from the drawing and the following description and claims.

In the drawing, Figure 1 is a longitudinal view of one modification of my device embodied in a cigarette holder and shows a cigarette in position in the end of the holder.

Figure 2 is a longitudinal sectional view of the cigarette holder shown in Figure 1.

Figure 3 is a longitudinal view of the inner tubular element 8 of Figure 2.

Figure 4 is a longitudinal view of a combined cleaning and baffling element, the intermediate tubular element 11 of Figure 2.

Figures 5, 5a, 5b and 5c are end views of different modifications of the intermediate tubular element 11.

Figure 6 is a longitudinal view of a combined positioning and closure device, the element 5 of Figure 2.

Figure 7 is a longitudinal view of the outer tubular element 2 of Figure 2.

Figure 8 is an enlarged longitudinal view partly in section and partly in elevation showing the assembly of the elements of Figures 3, 4, 6 and 7 and indicates the path taken by smoke in flowing therethrough.

Figure 9 is a transverse sectional view taken along the lines II—II of Figure 8.

Figure 10 is a longitudinal view partly in section of a modification of the invention for embodiment in a pipe stem and indicates separately the bowl end of a pipe stem and a modification of the element 8 of Figure 3 suitable for positioning therein. The assembly of the remaining elements to complete the pipe stem is also indicated.

Similar numerals refer to similar parts throughout the several views.

Referring to the drawing in greater detail, a device constructed according to the present invention may comprise a bit or mouthpiece 1 having a smoke passage 4 therethrough. An outer tubular member 2 is mounted, preferably separately, as by a threaded joint, on one end of the mouthpiece. The opposite end of the tubular member 2 is mounted, also preferably by an easily separable connection, on a tobacco holding member, such as cigar or cigarette holder 3 or pipe bowl 3'. An inner tubular member 8 is mounted in the rear end of the member 3, the smoke passage 9 through the member 8 forming a continuation of the smoke passage 7 through the member 3. Spacing means 10, which may suitably be in the form of notched radial fins, are mounted on the member 8, preferably at or near the end connecting with member 3. An intermediate tubular member 11 is positioned around the member 8 and is spaced therefrom and preferably also from the end of the member 3 by the spacing means 10. The inner surface of this member 11 makes an easily separable connection, preferably a loose frictional contact, with the spacing means 10 so that on disassembling the device this member is removed with the inner tubular member 3 and may then be easily detached therefrom, preferably by giving member 3 a slight jar or shake to avoid having to touch the member 11. This member 11 becomes soiled in use, and may be readily removed and replaced with a fresh member whenever desired. This member is preferably a cylinder having a diameter greater than half the inside diameter of the outer tubular member 2, in order to permit its ready alignment and closure by the means illustrated. These comprise a tubular member 5 having a closed outwardly projecting conical end of a maximum diameter greater than the inside diameter of the member 11 and preferably less than that of the outer member 2. The end of the member 11 is closed by being pushed against this conical surface when the device is assembled.

The member 5 is preferably mounted in the end of the mouthpiece 1 in such manner that it is a continuation of the smoke passage 4. Suitable means for the passage of smoke from the space between the member 11 and the outer member 2 into the smoke passage 4 of the mouthpiece 1 may comprise preferably one or more holes 6 in the member 5 between the points of contact with the member 11 and the mouthpiece 1, although the 55

smoke passage 4 may connect directly with this space, if desired.

While the device has been illustrated with the inner tubular member 8 connected with the tobacco holding member 3 and the member 5 connected with the mouthpiece 1, it is recognized that these positions may be reversed, member 8 being mounted in mouthpiece 1 and member 5 in member 3, without departing from my invention. The flow of smoke will then be reversed in its passage through the device, as will be understood. The manner of assembly illustrated is preferred, however, as it will be found to be cleaned more readily.

15 The manner of adapting the device for use with a pipe, as illustrated in Figure 10, in which the spacing means 10 is continued as a screw 10' of sufficient length to engage both the outer member 2 and the stem of the pipe bowl 3', may 20 also be varied, and any other suitable connection may be used as desired. For example, the projecting end of the member 8' may be in the form of a slightly tapered cylinder, making a tight frictional connection with a similarly 25 shaped recess in the stem of the pipe bowl 3'.

The intermediate tubular member 11 may also be closed at one end, as illustrated by 11' in Figure 10. In this case the alignment and closure member 5 may be omitted, or it may be used 30 simply as a spacing means 5a for positioning the closed end of the member 11. Figure 10 shows a section through one of three spacing means 5a which may be made as a part of the mouthpiece. The smoke passage 4 will connect directly 35 or through suitable openings in the spacing member 5a, with the space between member 11 and outer member 2.

The member 11 serves to clean and cool the smoke by increasing its path of flow through the 40 device and by the reversals of flow caused thereby which tend to throw out dust, droplets of moisture and other non-gaseous matter suspended in the flowing gas. This purifying action may be increased by constructing the member 11 of a suitable absorptive material, which 45 may even be somewhat pervious to gas. For example, it may be made so that at least one surface, inner or outer or preferably both, is made of absorptive paper, decolorizing carbon, or other 50 materials having similar functions. The flowing gas may also be filtered by placing a suitable filtering medium, such as loose cotton, in the annular spaces inside or outside this member, or both. It has been found, however, that such 55 filters, even when loosely matted, are difficult and inconvenient to insert and cause objectionably high pressure drop in use. A preferred filter may be prepared by attaching the ends of relatively short fibres to the surface of the member 11. 60 The fibres then extend into the flowing stream of gas and serve to filter and cleanse it of absorbable matter without unduly increasing the pressure drop through the device. The fibres are preferably of such length that, when attached, 65 they extend in their normal form, which may be straight, coiled or kinky, from the surface of the member 11 a distance about that of the width of the annular space in which they are to be when the device is assembled. Then, if they become 70 moist in use, they mat against the wall to which they are attached and are withdrawn at least partly from the flowing gas stream. Various modifications of member 11, in which fibres are attached to the outer, inner and both surfaces 75 of the member are illustrated in Figures 5a, 5b,

and 5c respectively. The fibres may consist of cotton, wool, silk, hemp, wood pulp, rayon and other natural and synthetic fibrous materials. They may be attached to the surface of the member 11 by any glue or cement suitable for the intended use or by other means, or they may be made a part of the surface by being mounted therein during its formation. A suitable method particularly for obtaining fibres attached to the inside surface is to apply the fibres to a sheet of material, suitably paper, which is then rolled and formed into cylinders of desired diameter and length. The fibres may be caused to stand out from the surface to which they have been attached, in the desired manner, by imparting an electrical, preferably an electrostatic, charge to them while the adhesive is drying or setting. They may also be used in the form of a fabric, such as a chenille or a transparent velvet, which has numerous fibres with loose ends projecting from the surface of the fabric. Such fabrics may be strengthened and the back of the fabric made more rigid by application to one or both sides of a sheet of paper, Cellophane, or other suitable material. Or sugar water or a solution of a suitable hard resin in a volatile solvent may be applied the back of the fabric and allowed to set preferably after the cylindrical form has been prepared.

While the invention has been illustrated and described herein in its preferred forms, it is to be understood that it may be used in other forms, embodiments and modifications without departing from the spirit thereof. This invention is not to be limited to any examples, applications or explanations, all of which have been presented herein solely for purposes of illustration, but is limited only by the following claims, in which it is desired to claim all novelty insofar as the prior art permits.

I claim:

1. In a smoking device, a device for treating the smoke comprising an inner tubular member, a separate intermediate tubular member open at each end and spaced from and surrounding the inner tubular member and having a free end extended beyond the end of the inner tubular member, means for centering said separate tubular member and closing the said free end comprising a conical surface projecting into said free end, and an outer tubular member spaced from and surrounding said separate tubular member whereby a continuous smoke passage is obtained in either direction through said inner tubular member, said smoke passage reversing in the space between said inner tubular member and said separate tubular member, and again reversing in the space between said separate tubular member and said outer tubular member.

2. A device according to claim 1 in which the inner tubular member has means mounted thereon for spacing said separate tubular member therefrom, said spacing means having a smoke passage therethrough connecting the space between said inner tubular member and said separate tubular member with the space between said latter member and said outer tubular member and making a non-threaded loose frictional contact with the inner surface of said separate tubular member.

3. A device according to claim 1 in which the means for closing the free end of said separate tubular member is carried by said outer tubular member and makes a loose frictional contact with the said free end.

4. A device according to claim 1 in which the said separate tubular member has a surface composed of absorbent material consisting of fibers extending a substantial distance into the open space adjacent said surface for filtering the smoke.

5. A device according to claim 1 in which the said separate tubular member has fibres attached to a surface thereof for filtering the 10 smoke.

6. A smoking device comprising a tobacco holding member, a smoke passage therethrough, an inner tubular member attached thereto and forming an extension of said smoke passage, 15 spacing means mounted on the outer side of said inner tubular member, a separate intermediate tubular member surrounding the inner tubular member and having a free end extending beyond the unattached end thereof, and making 20 a loose frictional contact between its inner surface and said spacing means, an outer tubular member spaced from and surrounding said separate member and connected at one end to said tobacco holding member, said spacing means having 25 a smoke passage therethrough connecting the space between said inner tubular member and said separate tubular member with the space between said latter member and said outer tubular member, a mouthpiece connected to the 30 other end of said outer tubular member and having a smoke passage therethrough connected with said last mentioned space, and means carried by said mouthpiece for aligning said separate tubular member and for closing the free 35 end thereof.

7. A device according to claim 6 in which the said separate tubular member has fibres attached to one surface thereof and extending into the adjacent smoke passage to filter the smoke.

8. A device according to claim 6 in which the said means carried by said mouthpiece, comprises a tube having a closed conical end having a maximum diameter greater than the inside diameter of said separate tubular member and less than that of said outer tubular member and spaced 45 therefrom, said cone projecting into and closing the free end of said separate tubular member,

said tubular member having an opening behind the cone connecting the smoke passage of the mouthpiece with the said last mentioned space.

9. A smoke filtering device comprising a substantially impervious tubular member having fibres mounted on and projecting from a surface thereof substantially each of said fibres having one free end.

10. A smoke filtering device comprising a substantially impervious tubular member having 10 fibres mounted on and projecting inwardly from the inner surface thereof, substantially each of said fibres having one free end.

11. A smoke filtering device comprising a substantially impervious tubular member having 15 fibres mounted on and projecting outwardly from the outer surface thereof, said fibres having one free end.

12. A smoke filtering device comprising a substantially impervious tubular member having 20 fibres mounted on and projecting radially from both inner and outer surfaces thereof substantially each of said fibres having one free end.

13. In a smoking device, a device for treating the smoke comprising an inner tubular member, 25 spacing means mounted on the outer side of said inner tubular member, a separate intermediate tubular member surrounding the inner tubular member and having a free end extending beyond the unattached end thereof, and making a non-threaded loose frictional contact at one end with said spacing means, means for closing said free end, an outer tubular member spaced from and surrounding said separate tubular member, said spacing means having a smoke passage there- 30 through connecting the space between said inner tubular member and said separate tubular member with the space between said latter member and said outer tubular member, whereby a continuous smoke passage is obtained in either di- 35 rection through said inner tubular member, said smoke passage reversing in the space between said inner tubular member and said separate tubular member, and again reversing in the space between said separate tubular member and said 40 outer tubular member.

JOHN G. TARRANT.
